KEY-ARRANGEMENT FOR FIXING WOODEN TOOL HANDLES

Anders Lind, Edsbyn, Sweden

Application October 22, 1942, Serial No. 462,986
In Sweden October 9, 1941

2 Claims. (Cl. 306—33)

It is known to fix a wooden handle to a tool by means of a plate provided with projections on one side and inserted into a slit on the end of the handle, into which slit a key afterwards is driven on the other side of the plate so that the projections are pressed into the wood of the handle.

According to the present invention the part of the plate that projects out of the slit is divided in flanges, one or several of which are bent over the key after it is driven into the slit and the other or the others of which have been bent in the opposite direction, before the plate is inserted into the slit so that this other flange or these other flanges serve as rabbets on the end of the handle and prevent that when the key is driven in and the projections, which can be barb-like formed, are pressed into the wood of the handle, longitudinal grooves are formed by the projections in the wood of the handle. In this way the plate and the key lock one another and the plate and the key are firmly fixed in the slit.

An example of the arrangement according to the invention is illustrated on the accompanying drawing.

Figs. 1, 3, 5 and 7 of the drawing are longitudinal sections through the end of the handle. Figs. 2, 4, 6 and 8 are the corresponding plan-views.

1 is a wooden handle on which a tool marked with dash lines is to be fixed. For this purpose a slit 2 is sawn in the end of the handle 1. A plate 3 of sheet-metal provided on the left side with barb-like projections 4 and on the upper end with two flanges 5 bent to the left and with one flange 6 directed upwards and arranged between the flanges 5 is inserted into the slit 2 so that the flanges 5 strike against the end of the handle 1 (Figs. 3 and 4). Afterwards a wooden key 7 is driven into the slit 2 on the side of the 40

plate 3 that has no projections. In this way the projections 4 are pressed into the wood of the handle 1 without sliding in the longitudinal direction so that no longitudinal grooves are formed in the wood of the handle and the projections 4 hold the plate 3 firmly fixed in the slit 2. Then the part of the key 7 that projects out of the slit 2 is sawn off (Figs. 5 and 6) and the flange 6 is bent over the end of the key 7 so that the key also is firmly fixed in the slit 2.

Having now particularly described the nature of my invention and the manner of its operation what I claim is:

1. Key-arrangement for fixing a wooden handle to a tool, comprising a slit on the end of said handle, a plate inserted into said slit and having one side provided with projections and the other side smooth, a key driven into said slit on the smooth side of said plate, flanges arranged on the upper end of said plate and projecting out of said slit, certain of said flanges being bent over said key after it is driven in and other of said flanges being bent in the opposite direction before said plate is inserted, to extend over the end of the handle.

2. Key-arrangement for fixing a wooden handle to a tool, comprising a slit on the end of said handle, a plate of sheet-metal inserted into said slit and having one side provided with projections and the other side smooth, a wooden key driven into said slit on the smooth side of said plate, a plurality of flanges arranged on the upper end of said plate and projecting out of said slit, certain of said flanges being bent over said key after it is driven in and other of said flanges being bent in the opposite direction before said plate is inserted, to extend over the end of the handle.

ANDERS LIND.
